JOEL S. LAWSON, OF ST. JAMES, NEW YORK, ASSIGNOR TO MEMCO ENGINEERING & MANUFACTURING COMPANY, INC., OF NEW YORK, N. Y., A CORPORATION OF NEW YORK

ELECTRIC SWITCH

Application filed July 17, 1925. Serial No. 44,294.

My invention relates to electric switches, and particularly to a switch capable of efficient service in an exposed or out-of-door installation in a high voltage line.

5 Among the objects of my invention may be mentioned, first, a generally improved layout of the switch by which a wide, quick break is attained; second, means by which the cooperating contacts of the switch are housed 10 against the elements both in open and closed circuit positions; third, contacts of improved construction; fourth, improved arcing horns; and fifth, various details of construction which will be hereinafter described or appear 15 in the accompanying drawings in which—

Fig. 1 is a side elevation of a switch in which my invention is embodied in one form; Fig. 2 is a plan view thereof;

Fig. 3 is an enlarged vertical section 20 through the driving gear of the switch;

Fig. 4 is an enlarged horizontal section through the cooperating switch contacts;

Fig. 5 is a section on the line 5—5, Fig. 4;

Fig. 6 is a plan view of a modified switch 25 construction;

Fig. 7 is a side elevation thereof.

The switch in both forms shown is designed for out-door installation in high voltage transmission lines, and falls in the general class of air break switches. A switch of 30 this character is customarily located at the head of a tower, of which only the beam 15 is shown, upon which the switch is secured. It will of course be understood that like switches 35 are installed in each phase of the power line, and are operated in unison.

Secured in fixed position and suitably spaced apart on the beam 15 are fixed post insulators 16 and 17. Adjacent the latter but 40 spaced further apart on the beam are swiveling post insulators 18 and 19. The foot pieces 20 of the latter are provided with downwardly extending studs 21 which pass through step bearings 22 secured to the beam

45 15. Attached to, and preferably integral with, the foot pieces 20 of the insulators 18 and 19, are crank arms 23 and 24 connected together by the rod 25 to cause the insulators to rotate in unison. A second crank arm 26 50 secured to and also preferably integral with

the foot piece of the insulator 19, but extending at an angle of approximately 90° to crank arm 23, is hinged to the switch actuating bar 27 (Fig. 2). Upon displacement of the bar 27 in the direction of its length, the 55 insulators 18 and 19 are caused to rotate in the same direction on their respective axes.

Inasmuch as the general construction is symmetrical with respect to the insulator pairs 17—19 and 16—18, a description of the 60 layout for one pair will enable that of the other pair to be understood. Fast with the head of the insulator 19 is an axial stub shaft 28 (Fig. 3), upon which is keyed a bevel gear 29. The stub shaft 28 is journalled in a boss 65 in the bottom 30 of a gear box. Projecting through the side walls 31 of the latter is a rock shaft 32, to which is keyed the gear segment 33 meshing with the bevel gear 29. Straddling the gear box and keyed to the projecting ends of the rock shaft 32 are the end 70 fork members 34 of the switch arm 35.

The gear box is provided with a cover 36 which may be detachably connected to the end walls of the gear box for ready removal 75 incident to inspection, lubrication and repair of the gear elements. A strut 37 extends from the gear box to the head of the adjacent fixed insulator 17, to which it is secured, so that the insulator posts 17—19 mutually 80 steady and support each other.

At the opposite end of the gear box is secured a terminal bracket 38 carrying a connector 39 to which the power cable 40 is secured. A flexible conductor 41 also secured to the connector 39 passes over the gear box cover to the switch arm 35. Cross braces 42 between the side members of the switch arm 35 form a lattice through which the flexible conductor 41 is laced, and thus 85 maintained in position. Preferably the flexible conductor comprises two strands (Fig. 2) between which the line current is distributed.

Jointed at 43 to one end of the arm 35 is 90 the contact-carrying extension 44 thereof. A radius arm 45, joined at 46 to the extension 44, is hinged at 47 to the cap of the stationary insulator 17. The radius arm carries an arcing horn 48 which cooperates 95 100

with the arcing horn 49 on opening of the switch.

Before describing further the details of certain of the switch elements, the general operation of the switch may be pointed out. When the actuating bar 27 is shifted in the direction of the arrow (Fig. 2), it causes rotation of the insulators 18 and 19, and thus the rotation of the bevel gears 29. The meshing engagement of the segments 33 causes the switch arms 35 to swing upward. While the extensions 44 partake bodily in the upward swing of arms 35, they form connecting links between these arms and the radius arms 45. The latter are of such length and their pivot points are so located, however, that the free ends of the extension links 44 at which the switch contacts are located, swing to the downwardly inclined position indicated in broken lines in Fig. 1. Upon the parting of the switch contacts, the current is transferred to the horn members 48 and 49, which eventually part near their tips and sweep rapidly to upright or slightly past upright position, as indicated in broken lines in Fig. 1. The reverse displacement of the actuating bar 27 returns the parts to the circuit-closing position illustrated.

It is important that the switch contacts be protected against accumulations of snow, sleet, etc. For this purpose I surround the contacts with sleet hoods 50 and 51, respectively, connected to the ends of the extension links 44 and surrounding the respective contacts. As noted from Figs. 4 and 5 the hood 50 is larger than the hood 51, and embraces the open end of the latter in circuit-closing position. The engaging surfaces of the contacts are thus completely housed against the elements. In open circuit position, the contacts hang downward, and the hoods form effective rain, snow and sleet sheds by which the parts are kept in proper condition for re-establishment of the circuit when the contacts are again moved to circuit-closing position.

The contacts (Figs. 4 and 5) are of an improved construction to obtain good electrical connection. One of the contacts consists of a rigid blade 52, which may be integral with the lug 53 to which the terminals 54 of the flexible conductors 41 are directly connected by screw bolts 55. Bolts 56 rigidly secure this contact and its associated members to the end of the link 44. The cooperating contact comprises a pair of spring straps 57 having spaced parallel brushes 58 adapted to embrace between them the rigid contact blade 52, the brushes being connected by guide bevels 59 and spring bends 60 to their respective body members 57. Auxiliary plate springs 61 bear against the outer faces of the brushes 58 and aid the spring bends 60 in effecting an efficient frictional

engagement with the blade 52. The attaching ends of the springs 61 and the ends of the contact straps 57 are riveted to a spacer 62 through which pass the bolts 63 by which the contact and the shield 51 are secured to the link 44. The ends of the contact 57 extend beyond the spacer 62 and are riveted to the block 64 which carries the connector 65 for the flexible conductor 41.

The arcing horns 48 and 49 (Figs. 1 and 2) are secured to the free ends of the radius bars 45. One of the horn members, viz., 48, comprises a pair of independent rods, the free ends of which 66 are offset in opposite directions to guide the associated horn member 49 into engagement therewith on the closing of the switch. The opposite ends of the rods are passed through angled flanges 67 at the ends of the opposite side members of the radius bars and secured at 68 thereto.

The cooperating horn member 49 has the form of a straight sided loop, the side rods of which are connected by a V-bridge 69, the rounded nose 70 of which serves as an entering wedge which aids in properly locating this member with respect to the cooperating arms of the horn member 48 when the circuit is closed. The horn members are in electrical connection with the radius bars 45, and these in turn with the contact carrying extension 44 of the arm 35 through the bolt members 68 which pass through both.

In Figs. 6 and 7, is illustrated a modified switch construction which may be used to advantage in circuits of lower voltage. In this construction, the contact carrying link 75 is hinged at 76 to the arm 77 pivoted at 78 to a terminal bracket 79 carried by a clamp 80 at the top of a fixed insulator 81. The radius member which is pivoted at 82 to the link 75, constitutes in this construction, the switch operating member. It comprises a bracket 83 secured to or integral with a clamp 84 at the head of a rocking insulator 85, the base 86 of which is clamped to a rock shaft 87. To the crank arm 88 of the latter is pivoted at 89 the operating rod 90. A second crank arm 91 is connected through link 92 with the crank arm 93 on the second crank shaft 94, upon which the corresponding insulator 85 and its associated parts are mounted.

To open the switch the bar 90 is pulled downward, thus causing the insulators 85 to rock apart, and shifting the contacts to the position indicated in broken lines in Fig. 7. It will be noted that the position of the sleet hoods, etc. is substantially identical with that illustrated in the construction first described.

Various other modifications of construction will readily occur to those dealing with the problem which do not depart from what I claim as my invention.

I claim—

1. A high tension electric switch, comprising a pair of pivoted radius members inclined

toward each other in closed circuit position, arcing horns carried by said radius members and engaging each other in circuit closing position, but moving upward and away from each other on movement of the radius arms to open circuit position, in combination with a toggle system comprising a contact arm connected to the radius arms and substantially horizontal in closed circuit position, but displaced to inclined position with the contact end downward on movement of the parts to open circuit position.

5 2. A high tension circuit breaker comprising two pivotally mounted contact members, arcing horns connected therewith, sleet hoods movable with and housing said contacts, said sleet hoods telescoping in closed circuit position of the contacts to protect the contacts, in combination with linkage mechanism to 10 move said contacts between open and closed circuit position.

15 3. A high tension circuit breaker comprising two movable contact members, arcing horns connected therewith, sleet hoods housing said contacts and movable therewith, said sleet hoods telescoping in closed circuit position of said contacts to protect said contacts, in combination with means to move said contacts between open and closed circuit position 20 and in open circuit position of said contacts to face said sleet hoods downwardly.

25 4. A high tension circuit breaker comprising two pivotally mounted contact members, arcing horns connected therewith, sleet hoods 30 housing said contacts and movable therewith, in combination with means to move said contacts between open and closed circuit position, said means moving said contacts in substantially a straight line path during the last portion of their closing movement whereby 35 said sleet hoods may telescope to protect said contacts.

In testimony whereof I have signed my name to this specification.

45 JOEL S. LAWSON.
